UNITED STATES PATENT OFFICE.

BEN A. BUCHORN, OF DIME BOX, TEXAS.

COMB-CLEANING DEVICE.

1,264,486.

Specification of Letters Patent. Patented Apr. 30, 1918.

Application filed May 2, 1917. Serial No. 166,016.

To all whom it may concern:

Be it known that I, BEN A. BUCHORN, a citizen of the United States, residing at Dime Box, in the county of Lee and State 5 of Texas, have invented certain new and useful Improvements in Comb-Cleaning Devices, of which the following is a specification.

My invention relates to improvements in 10 comb cleaners, and it consists in the constructions, combinations, and arrangements herein described and claimed.

An object of my invention is to provide a comb cleaner consisting essentially of a 15 supporting bracket having ears whereby it may be secured to a wall, wires or cords being strung upon the bracket so that a comb may be stroked thereacross and cleaned.

Other objects and advantages will appear from the following specification, reference being had to the accompanying drawing, in which:

Figure 1 is a perspective view of a comb 25 cleaner embodying the features of my invention;

Fig. 2 is a detail cross section showing the manner of binding the wires upon the bracket.

By referring to Fig. 1 it will be observed 30 that the comb cleaner comprises essentially a bracket including a wall plate 1. The wall plate 1 is provided with ears 2 at its upper and lower ends, the ears 2 being 35 apertured to receive securing screws whereby the bracket is secured upon a wall.

The bracket also includes a forwardly extending ledge 3 which is an integral part of the wall plate 1 and is arranged preferably at right angles thereto.

The ledge 3 is pierced by a series of perforations 4 which extend crosswise of the ledge and are arranged near the front edge thereof as shown in Fig. 1. The upper edge 45 of the wall plate 1 is similarly pierced by a transverse series of perforations 5, the perforations 5 being equal in number to perforations 4.

Wires 6 are threaded into the openings 50 4 and 5 it being understood that of necessity the perforations 4 and 5 will be close together so that when the wires 6 are threaded therethrough, they too will be positioned in close relationship so that they may enter

approximately each of the spaces between 55 the teeth of a comb when a comb is stroked thereover to free the teeth of accumulations of dirt.

The ends of the wires 6 are twisted in any suitable manner over the substantially O- 60 shaped fastening bails 7 as at 8 in Fig. 2. The wires 6 are first threaded through the respective openings 4 and 5 and the free ends thereof are then twisted about one of the members of the respective bails 7. Since 65 the bails 7 fit the members 1 and 3 of the bracket very closely, it follows that by moving the bail members downwardly or inwardly as the case may be, the wires 6 are drawn taut.

The operation of the device is as follows: The wall plate 1 is secured upon a wall through the medium of screws which are passed through the ears 2. The wires 6 75 are disposed at such an angle that a comb may be stroked thereover most conveniently. This angle is one of about sixty degrees and is shown approximately so in the drawing. This angle, of course, may vary although it has been found that a comb may be 80 stroked against the wires or cords and in this particular position more conveniently and with the best results.

As above stated the comb is now stroked over the wires or cords until all accumulations of dirt at the base of the teeth are dislodged by reason of the entrance of the wires or the strains of the cord in the spaces between the teeth of the comb.

It is a matter of common knowledge that 90 the cleaning of the comb is a thing to be avoided because of the almost certain dissatisfaction which follows when it is attempted to stroke a comb over a string which is tied at one end and held in the 95 other hand or upon the edge of a card. With the above methods the operator's clothing and fingers are sure to become soiled. With the use of my device, when a comb becomes clogged it is simply stroked 100 over the wires or cords of the cleaning device which is secured upon a wall in some convenient place. A few strokes will suffice to dislodge all accumulations from the teeth of the comb which may then be used as 105 formerly.

While the construction of the device as illustrated in the drawing is that of a gen-

erally preferred form, obviously modifications and changes may be made without departing from the spirit of the invention or the scope of the claims.

5 I claim:

1. In a comb cleaning device of the class described, the combination of a supporting frame, said frame having a plurality of perforations formed therethrough, cleaning 10 wires carried by said frame and projecting through said perforations, substantially O shaped bails positioned upon said frame, the construction of said bails causing the same to fixedly bind thereon, said wires being connected to said bails, thus being permanently mounted upon said frame, said bails being adapted to be moved upon said frame to a desired position, thus drawing said wires through said perforations for increasing the 15 tension of said wires and retaining the same in taut position.
2. In a comb cleaning device of the class described, the combination of a wall plate having ears extending from the ends thereof, thus permitting the wall plate to be secured to a support, a horizontal ledge formed upon said wall plate and projecting at right angles thereto, thus forming a substantially L shaped supporting bracket, said 20 wall plate having a row of perforations adjacent the upper end thereof, said ledge having a row of perforations adjacent the outer end thereof, cleaning wires extended through said perforations, thus causing said wires 25 to extend substantially diagonally of the

frame, substantially O shaped bails slidably mounted upon said wall plate and said ledge, the construction of said bails causing the same to frictionally bind in a set position upon said wall plate and ledge, the 40 projecting ends of said wires being secured to said bails beneath said ledge and behind said wall plate, thus permitting said bails to be moved along said wall plate for drawing the strands through said perforations, 45 thus increasing the tension of the strand for holding the same in taut conditions at all times.

3. In a comb cleaning device of the class described, the combination of a supporting 50 frame, said frame having a plurality of perforations formed therethrough, cleaning wires carried by said frame and projecting through said perforations, bails slidably mounted upon said frame, means formed for holding the same against accidental movement, said wires being connected to said bails, thus being permanently mounted upon said frame, said bails being adapted to be moved upon said frame to a desired 55 position, thus drawing said wires through said perforations for increasing the tension of said wires and retaining the same in taut condition.

In testimony whereof I affix my signature 60 in presence of two witnesses.

BEN A. BUCHORN.
